INVENTOR.

F. I. GORTON

UNITED STATES PATENT OFFICE.

FRED I. GORTON, OF NORTH ATTLEBORO, MASSACHUSETTS.

DESIGN FOR A WATCH-FOB.

SPECIFICATION forming part of Design No. 36,168, dated December 16, 1902.

Application filed October 16, 1902. Serial No. 127,609. Term of patent 7 years.

To all whom it may concern:

Be it known that I, FRED I. GORTON, a citizen of the United States, residing at North Attleboro, in the county of Bristol and State of Massachusetts, have invented a certain new, original, and ornamental Design for a Watch-Fob or Similar Article, of which the following is a specification.

The accompanying drawing shows a watch-fob embodying my design. As disclosed therein, the leading or material feature of my design consists in a substantially oblong body portion *a*, provided upon the face thereof with a converging loop in relief, pendent from which is a spirally-ribbed circular ornament surmounting the representation of a camel *c*, also in relief. Above the loop before mentioned and transversely to the body portion

of my watch-fob, in relief, is the representation of a simitar *b*. 20

While my design is shown only as embodied in a chain, it is evident that the same is applicable to badge-streamers and similar articles of wearing-apparel.

Having described my invention, what I claim as new, and desire to obtain by Letters Patent, is—

The ornamental design for a watch-fob or similar article, as herein shown and described.

In testimony whereof I have affixed my signature in presence of two witnesses.

FRED I. GORTON.

Witnesses:

ANDREW J. NEUSCHNEZ,
FRED B. BYRAM.
